DESIGN FOR AN ASH RECEPTACLE

Gladys Enid Joseph Alexander, Scarsdale, N. Y.

Application December 28, 1942, Serial No. 109,152

Term of patent 14 years

To all whom it may concern:

Be it known that I, Gladys Enid Joseph Alexander, a subject of Great Britain, residing at Scarsdale, in the county of Westchester and State of New York, have invented a new, original, and ornamental Design for Ash Receptacles, of which the following is a specification, reference being had to the accompanying drawing, forming part thereof.

In said drawing:

Fig. 1 is a top plan view of an ash receptacle showing my new design.

Fig. 2 is a side elevational view.

Fig. 3 is a bottom plan view.

Fig. 4 is a cross sectional view on the line 4—4 of Fig. 2.

I claim:

The ornamental design for an ash receptacle, as shown.

GLADYS ENID JOSEPH ALEXANDER.
